GEORGE H. OSGOOD, OF TACOMA, WASHINGTON

PRESSURE BAR FOR VENEER MACHINES

Application filed June 7, 1930. Serial No. 459,699.

This invention relates to those pressure bars for veneer machines having a rotary contact member, or nose piece, and has special reference to the means for lubricating the said rotary pressure member. The objects of my invention are to provide an economical and effective means of supplying the said rotary member with lubricant, and to distribute such lubricant evenly along its entire length.

I attain these and other objects by the devices, and arrangements illustrated in the accompanying drawings, in which—

Fig. 1 is a vertical cross-section of a pressure bar in which the rotary nose member has its bearings in a horizontal and an inclined plane, and showing the means for lubricating the nose along its entire length; Fig. 2 is a similar view showing a variation in the lubricating means as used when the bearings for the rotary nose member are mounted in the horizontal plane; Fig. 3 is a front view, on a small scale, showing the lubricating means largely in diagrammatic form; and Fig. 4 is a section on the line 4-4 in Fig. 1, of the end of the oil cavity, showing the plug therein.

Similar numerals of reference refer to similar parts throughout the several views.

In veneer machines, the knife engages the wood to cut a slice or sheet from the block or log, said knife extending across the full width of the block. In order to prevent the cutting action of the knife from developing into a splitting action, it is necessary to apply a heavy pressure to the surface of the wood adjacent to and relatively in front of the cutting edge of the knife. In order that the action of the pressure bar, by which such pressure is applied to the wood, may be uniform along its entire length, it is necessary that it be made very strong and stiff in the plane of the pressure. Until recently the only form of pressure bar which could be made strong enough to apply a uniform and effective pressure across the entire width of the block, had a slightly rounded fixed nose, but I have devised means whereby the nose may have a rolling contact with the wood. On account of the fact that such contact

must be made very close to the cutting edge of the knife it is absolutely necessary that such roller be of very small diameter and, therefore, it must be supported continuously for its full length. Now, the wood only engages a small area of the roller while the bearing blocks, which are mounted in the strong, stiff bar and which support and give the required backing for the roller, engage from two-thirds to three-quarters of its surface, hence it is evident that the coefficient of friction of the bearing blocks must be relatively low in comparison with that of the wood in order that the roller may be turned without external aid or with as low a consumption of additional power as is possible. Under some conditions it is preferable to have the roller, or pressure contact member, rotated by an independent means but, as a rule, such auxiliary power may be eliminated if the friction between the roller and the supporting bearing blocks may be reduced sufficiently. The purpose of this invention is to apply a lubricant to the bearing blocks in such manner that the entire length of the roller is equally and uniformly lubricated.

Referring to the drawings, the main strong-back member 1 is provided with a head 2 in which two slots 3 and 4 extend the full length of the bar 1. The slot 3 is horizontal and the slot 4 is inclined at about forty-five degrees upward and towards the rear. Both slots 3 and 4 lead backward from a cavity 5 formed in the extreme forward edge of the head 2. The rotary nose 6 is supported in said cavity 5 by means of two bearing blocks.

In the form shown in Figs. 1, the bearing blocks 7 lie in the slot 3 and the bearing blocks 8 lie in the slots 4. These bearing blocks 7 and 8 are provided with concaved front edges in which the rotary nose 6 lies. The two said blocks 7 and 8 are separated by a portion of the cavity 5.

Oil is introduced into the cavity 5, between the bearing blocks 7 and 8 and therefore contacts directly with the surface of the rotary nose 6.

I prefer to supply the oil by any suitable means, such as the hand-pump 9 from the

reservoir 10, to a line pipe 11 which connects, at suitable intervals in the length of the bar 1, with passages 12 through the said bar. Other pipes 13 connect the lower ends of the passages 12 with ducts 14, made in the lower bearing block 7 and leading direct into the cavity 5 between the bearing blocks 7 and 8. Each pipe 13 passes loosely through a hole in the lower part of the head 2 and screws 10 into the block 7, thus permitting the said block to be adjusted by means of its backing screws 15.

In the form shown in Fig. 2, the rotary nose 6 is mounted in a compound bearing block 15 positioned in the lower horizontal slot 3. This bearing block comprises a main block 16, from which the upper front portion has been cut away, with a supplemental block 17 fitted in said cut portion and receiving its pressure from the rear part of the main block 16. These two blocks are concaved-grooved at their outer edges to receive the rotary nose 6 between them. The pipe 13, above described, screws into the rear of the block 16 and connects with a duct 18 leading therefrom to the space 19 between the said blocks.

The ends of the cavity 5, in the form illustrated in Fig. 1, or the space 19, in the form illustrated in Fig. 2, may be closed by means 30 of a plug 20 of felt, or by any other suitable means.

Thus it will be seen that my lubricating means permits the effective lubrication of the rotary nose 6 throughout its entire length, 35 with substantially uniform effect, and that therefore the friction of the nose on the metal bearing blocks, in spite of the very high pressure transmitted to said nose, is substantially less than the friction between the nose and the wood being cut, for, though some lubricant may be interposed between the wood and the nose, the wood itself is dry and the friction between it and the nose is not materially reduced.

Having described my invention, what I claim is:

1. In a pressure bar for veneer machines, a main bar; a rotary nose; a plurality of separated complementary bearing blocks supported in said main bar and together supporting the rotary nose between them; and means for supplying a lubricant in the space between said bearing blocks.

2. In a pressure bar for veneer machines, a main bar; a rotary nose; a plurality of separated complementary bearing blocks mounted in said main bar and together supporting the rotary nose between them; a lubricating passage in one said block and leading to the space between said complementary blocks; and means to supply a lubricant through said passage to the space between said complementary blocks.

3. In a pressure bar for veneer machines, a

main bar; a rotary nose; a plurality of separated complementary bearing blocks mounted in said main bar and together supporting the rotary nose between them; a lubricating passage in one said block and leading to the space between said complementary blocks; a lubricant-bearing pipe leading to said passage; and means for supplying lubricant to said pipe.
